(57) **CLAIM**

The ornamental design for an exhaust crossover assembly, as shown and described.

DESCRIPTION

FIG. 1 is a front, left perspective view of the automobile exhaust collector showing the new design;

FIG. 2 is a top plan view thereof;

FIG. 3 is a bottom plan view thereof;

FIG. 4 is a side elevational view thereof;

FIG. 5 is a front elevational view thereof; and,

FIG. 6 is a rear elevational view thereof.

The structural features and indicia depicted by broken lines have been shown for the purpose of illustrating portions of the automobile exhaust collector that form no part of the claimed design.

The thin solid lines in the views have been provided for the purpose of illustrating the uniformity of the planar surfaces and the contour of the curved surfaces and are not a claimed surface pattern.
